UNITED STATES PATENT OFFICE.

JOHN C. McGEE, OF NEW YORK, N. Y.

RIPPING DEVICE.

1,405,529.

Specification of Letters Patent.

Patented Feb. 7, 1922.

Application filed August 11, 1920. Serial No. 402,869.

To all whom it may concern:

Be it known that I, JOHN C. McGEE, a citizen of the United States, and a resident of New York, in the county of New York and State of New York, have invented certain new and useful Improvements in a Ripping Device, of which the following is a full, clear, and exact specification.

This invention relates to a class of cutting implements.

My invention has for its object primarily to provide a device designed to be employed especially by tailors, dressmakers and other persons for ripping stitched seams of cloth and like material by using cutting blades commonly made for safety razors, it being generally accepted that blades of this class may be employed more effectually for accomplishing such work without danger of cutting the material than the use of knives or scissors of ordinary types as well as enabling the work to be executed with facility, and which is of a form adapted to allow the utilization of safety razor blades when discarded by persons owing to dullness from shaving. The invention consists essentially of a holder with a grooved body provided between two yielding walls so that a safety razor blade may be removably inserted in the groove, and in the central parts of the walls lengthwise of the groove are two opposed recesses communicating with the groove for receiving and holding forms of blades having an enlarged or beaded lengthwise edge so that the cutting edge of the blades will extend beyond the mouth of the holder. To provide for also accommodating in the holder types of flat blades having two cutting edges, in the holder at the bottom of the groove is a substantially V-shaped recess which communicates with the groove, and protruding into the groove from parts of its walls above the opposed recesses may be two complementary members for removably clamping the blades in the holder to prevent tendency of lateral movements of the blades.

A further object of the invention is to provide a ripping device of a simple and durable construction which may be made in any suitable shape and size.

With these and other objects in view, the invention will be hereinafter more fully described with reference to the accompanying drawing forming a part of this specification in which similar characters of reference in-

dicate corresponding parts in all the views, and will then be pointed out in the claim at the end of the description.

In the drawing, Figure 1 is a side elevation of one form of ripping device embodying my invention.

Fig. 2 is a perspective view of the holder used in the device.

Fig. 3 illustrates sectional views each taken on the line 3-3 of Fig. 2, and which show in dotted lines the manner of using different forms of safety razor blades in the holder of the device, and

Fig. 4 illustrates different types of razor blades which may be used with the holder.

The device has a holder 10 which may be made of any suitable material in any desired size, and this holder is composed of a body part 11 of somewhat an elongated substantially rectangular shape constructed of two spaced walls 12 and 13 with one of their lengthwise edges being joined together, as at 14, to provide a groove 15 therebetween having its mouth or entrance extending from the joined edge 14 through the ends and second lengthwise edge of the body part. The body part 11 is preferably made of spring sheet metal to provide yielding walls, and the walls are spaced apart so that a safety razor or blade may be freely inserted into the groove 15.

In the central part of the inner face of the yielding wall 12 and extending lengthwise of the wall is a recess 16, and in the central part of the inner face of the yielding wall 13 and also extending lengthwise of the wall is a recess 17. The recesses 16 and 17 are in opposition as well as being in communication with the groove 15, and both of these recesses may be of any appropriate shapes and sizes, though each recess is preferably concaved transversely as illustrated.

In the bottom of the groove 15 between the walls of the body part 11 is another recess 18 of approximately a V-shape in cross section, and this recess also communicates with the groove 15 under the opposed recesses 16 and 17.

Protruding into the groove 15 from opposed parts of the walls 12 and 13 of the body part 11 of the holder are two complementary members 19 and 20 which may be in the forms of ribs extending lengthwise of the walls above the recesses 16 and 17, and these ribs are in closely spaced opposition so that a safety razor blade may be re-

movably accommodated therebetween as well as being clamped against accidental displacement or liability to move laterally in the holder when the blade is used. Protruding from one end of the body part 11 of the holder may be a tang, as 21, and on the tang may be mounted a handle, as 22, of a suitable type to allow the device to be conveniently employed for ripping the 10 stitches of seams of cloth and other material.

In the holder 10 as thus constructed I may employ any of the forms of blades, as 23, 24, 25, Fig. 4, which are of types commonly 15 used in safety razors, especially blades that have been dulled by use. The form of the blade 24 has a single cutting lengthwise edge 26, and its second lengthwise edge is enlarged or provided with a marginal bead, 20 as 27. This form of blade is of a size so that when applied to the holder 10 by being slidably passed endwise into the free open end of the groove 15 of the body part of the holder the bead 27 will be disposed in 25 the recesses 16 and 17, while the cutting edge part 26 of the blade will extend beyond the mouth of the groove, as shown in Fig. 1. The forms of the blades 23 and 25 each have two lengthwise cutting edges 28 and 30 29, and when either of these blades are inserted in the groove 15 of the holder 10 one of their cutting edges will be disposed in the V-shaped recess 18 of the holder, while the second cutting edge of the blade ex- 35 tends some distance beyond the mouth of the groove 15. The grooved body part 11 of the holder is made of a size relative to the sizes of standard safety blades so that when the blades are removably mounted in the 40 holder the cutting edge of each blade will protrude sufficiently from the holder to enable the projecting part of the blade to be

passed between strips of stitched cloth and like material in a manner for readily cutting the stitches, besides preventing tendency of the blade to damage the material. 45

In the foregoing description, I have embodied the preferred form of my invention, but I do not wish to be understood as limiting myself thereto, as I am aware that modifications may be made therein without departing from the principle or sacrificing any of the advantages of this invention, therefore I reserve to myself the right to make such changes as fairly fall within the scope 55 thereof.

Having thus described my invention, I claim as new and desire to secure by Letters Patent:

A holder for safety razor blades comprising a tang, and jaws at the ends thereof and integral with the tang, said jaws inclining outwardly from their juncture to a substantially intermediate point, with the said intermediate points of the opposite jaws outwardly arched and thence curving inwardly near the outer edges of the jaws into close proximity and forming, with the outwardly inclining portions, spaced bearings for engaging double edged blades near their edges 60 when inserted between the jaws, the outwardly arched intermediate points being arranged and formed for the reception of the edge bead of a single edged blade therebetween, with the intermediate portion of 65 said blade held between said inwardly curved outer portions of the jaws. 70

This specification signed and witnessed this 10th day of August, A. D. 1920.

JOHN C. McGEE.
